HIGH-FREQUENCY OSCILLATORY APPARATUS

Carlton E. Bessey, Red Bank, N. J.

Application January 15, 1945, Serial No. 572,914

9 Claims. (Cl. 250—36)

1

The present invention relates to electric systems, and more particularly to oscillatory systems. From a more specific aspect, the invention relates to high-frequency systems.

An object of the invention is to provide a new and improved electric system of the above-described character.

A further object is to provide a novel radio-frequency generator, adapted for use with either ordinary or ultra-high frequencies.

A further object still is to increase the frequency stability.

Another object is to obtain a higher frequency range than is attainable with conventional systems employing the same or similar equipment, such as the vacuum tubes.

Another object aims to increase the plate efficiency for the same frequency spectrum.

Still another object is to provide a system of the above-described character that shall be compact, simple of construction, mechanically rigid, efficient and inexpensive.

The invention will now be more fully explained in connection with the accompanying drawings, in which Fig. 1 is a circuit diagram embodying the invention in preferred form; Fig. 2 is a similar diagram, but simplified, and with parts omitted, in order to clarify the description; Figs. 3 and 4 are views similar to Fig. 1 of modifications; Figs. 5 and 6 are explanatory curves; and Fig. 7 is an explanatory graph.

An oscillator is shown comprising a vacuum or electron tube 2 having a cathode 4, indirectly heated by a filament 6, a control-grid electrode 7 and an anode or plate 8. Other types of cathode 4 may, of course, be employed; for example, the directly-heated type illustrated in Fig. 4. The filament 6 is supplied with heating current from any desired energy source (not shown) by lead conductors 10, preferably crossed and intertwined, as shown, to reduce losses.

This oscillator, for convenience, may be termed a first oscillator. It comprises an output or plate circuit and an input or grid circuit. The first part of the output and the input circuits is the same. It may be traced from the cathode 4, by way of conductors 12 and 14 (shown continuous in Fig. 2, but connected through grounds 50 in other figures), through an energizing plate-supply B battery 16 and, by way of a conductor 18, to a terminal 20. In Fig. 2, the terminal 20 is shown grounded at 22, through a large by-pass condenser 24, by way of a conductor 25. In Figs. 1 and 3, the connection of the conductor 25 to the ground 22 is shown by way of an intermediate

2

ground 52. In Fig. 4, the terminal 20 is omitted, for a reason that will hereinafter appear. The cathode 4 is also shown grounded at 22; by way of the conductor 12 and a conductor 23, in Fig. 2; by way of the conductors 12 and 14 and the ground 50 in Figs. 1 and 3; and by way of the conductor 12 and the ground 50 in Fig. 4. From the terminal 20, the said first part of the output and input circuits continues, by way of a conductor 26, grounded through its connection to the grounded terminal 20, to a similarly grounded fixed terminal 28 of a conducting impedance element 30. The terminal 28 is replaced by a terminal 272 in Fig. 4.

From the grounded terminal 28, in the systems of Figs. 1, 2 and 3, the output circuit is completed, through an output-impedance portion 32 of the impedance element 30, to a fixed terminal 34 thereof and, by way of a conductor 36, to the anode 8. The remainder of the input circuit may be traced from the grounded terminal 28, through an input-impedance portion 38 of the impedance element 30, to an adjustable terminal 40 thereof; from the adjustable terminal 40, through a grid-coupling condenser 42, the function of which is to prevent the voltage of the battery 16 from being applied directly to the control electrode 7, to a terminal 44; and from the terminal 44, by way of a conductor 46, to the control electrode 7. A grid resistor 48, connected between the terminal 44 and the ground 22, serves as a bias for the input circuit. A choke coil 49 (Fig. 4), of large impedance at the resonant frequency of the oscillator, may be connected in series with the bias resistor 48 to reduce the shunting effect of this resistor 48 on the resonator circuit.

The conductor 14 may be connected adjustably to a conventional one-quarter-wavelength-matching cathode-tuning stud-tube 54 for enclosing the filament lead conductors 10. This variation of the inductance in the filament circuit is desirable when extremely high frequencies are employed.

For convenience, because of the sequence shown, the fixed terminals 34 and 28 and the adjustable terminal 40 will hereinafter be referred to as first, second and third terminals, respectively. The output circuit is therefore connected between the first and second terminals, and the input circuit between the second and third terminals.

It will be observed that the portion 32 of the impedance element 30 is connected in the output circuit of the oscillator, between the cathode 4 and the anode 8, and that the portion 38 of the

impedance element 30 is connected in the input circuit, between the cathode 4 and the control electrode 7. As these impedance parts 32 and 38 are inductive, therefore, this oscillator is of the ultra-audion or Colpitts type. The feed-back circuit involves the anode to the cathode and the grid to the cathode. Oscillations may therefore be produced through proper choice of the values of these impedances and the other parameters of the oscillator.

The parameters are properly chosen to start with, and final adjustments may be made by adjustment of the third terminal 40. For a particular tube 2, there is a particular optimum plate dissipation, as determined by the manufacturer of the tube. The third terminal 40 should be so adjusted that the tube shall not operate beyond its rated capacity. The maximum allowable radio-frequency potential will then be had at the first terminal 34.

If the third terminal 40 should be continuously adjusted away from its optimum position, toward the second terminal 28, for example, the grid 7 would receive less and less voltage; this follows from the fact that, as the second terminal 28 is grounded, it is at zero voltage. If, on the other hand, the third terminal 40 should be adjusted away from its optimum position in the opposite direction, too great a drive would be impressed upon the grid 7, with the resulting dissipation of too much power in the input circuit of the tube 2.

The impedance element 30 contains also an output-impedance part 132 and an input-impedance part 138, corresponding, respectively, to the output-impedance part 32 and the input-impedance part 38, and respectively connected in the output and the input circuits of a second ultra-audion or Colpitts-type oscillator. The second oscillator comprises a vacuum or electron tube 102 having a cathode 104, heated by a filament 106, a control-grid electrode 107 and an anode or plate 108. The second oscillator is substantially the same as the first oscillator, and the same reference numerals are therefore applied thereto, though augmented by 100. The same battery 16 is shown supplying the plate voltage of the second oscillator, through connecting a ground 150 to the ground 50. The conductor 18 and the terminal 28, therefore, may be common to the output and the input circuits of the two oscillators. The output circuit of the second oscillator is connected between sequentially arranged fourth and fifth fixed terminals 134 and 128 of the impedance element 30, corresponding to the first and second fixed terminals 34 and 28. The input circuit of the second oscillator is connected between the fifth terminal 128 and an adjustable sixth terminal 140, the latter corresponding to the adjustable third terminal 40.

Where tuning over a wide frequency spectrum is desired, a variable condenser 35 may be connected between the terminals 34 and 134. The function of the by-pass condenser 24 is largely to maintain the terminals 28 and 128 at ground radio-frequency potential, in the event that unbalanced conditions should arise in the oscillatory circuit, and to prevent any radio-frequency energy or standing waves from becoming impressed upon the battery circuit; also to eliminate harmonics.

It will be observed that the impedance element 30 is continuous, as it closes in upon itself, and does not have any free ends. The resonator of the present invention may, therefore, be referred to as of the re-entrant type. It is shown diagram-

atically in Figs. 1, 2 and 4, as an inductance winding coiled into the form of a toroid. The beginning and the end of the inductance winding are connected together, so as to coincide, thereby forming a continuous winding each turn of which has magnetic linkages with the adjacent turn on either side.

The oscillatory system of the present invention, therefore, comprises two oscillators, so connected symmetrically, in cascade, through the continuous impedance 30, that the output circuit of each oscillator shall be coupled to, so as to feed into, the input circuit of the other oscillator. The impedance element 30 thus constitutes a continuous transformer. The output energy in the output-impedance part 32 of the first oscillator will therefore be induced by transformer action in the input-impedance part 138 of the second oscillator, and the output energy in the output-impedance part 132 of the second oscillator will be induced by transformer action in the input-impedance part 38 of the first oscillator.

With the connections above described, it is possible to have the various parts of the impedance element 30 in proper phase for attaining this end. This may be understood by referring to the graph of phases illustrated in Fig. 5, which represents a simplified form of the impedance element 30, shown, not as a continuous element, but as a straight-line two-ended conductor one wave-length long, supporting a standing-voltage wave between its two ends 28, 28. The second and the fifth terminals 28 and 128 are there shown at the same zero or grounded potential. The first and the fourth terminals 34 and 134, as indicated by the corresponding ordinates of Fig. 5, should be at maximum radio-frequency potential, but of opposite sign, and substantially 180 degrees out of phase with respect to the phase of the terminals 28 and 128. The adjustment of the third and the sixth terminals 40 and 140 should be such as to provide proper grid drive for the tubes 2 and 102. The potential of the terminal 40 will be between the zero or ground of the terminal 28 and the potential of the terminal 134; and the potential of the terminal 140 will be between the zero or ground of the terminal 128 and the potential of the terminal 34, of substantially opposite phase to that of the terminal 134. If the phase angle of the input circuit should happen not to be of the right value, that may be readily corrected for by adjustment, as of the cathode tuning stud 54. The grid-coupling condensers 42 and 142 should so couple the respective grids 7 and 107 of the tubes 2 and 102, respectively, to the terminals 40 and 140, as to attain the proper voltage and phase relations for the grid drive of these two tubes.

Using point 128, for example, as a reference point, and progressing around the resonator in a clockwise direction, a point or terminal will be reached where the grid 107 of the vacuum tube 102 may be attached to provide proper excitation for the vacuum tube 102. The next point or terminal thus progressively reached will be the point 34, which is connected to the plate 8 of the vacuum tube 2, etc.

In operation, the filaments 6 and 106 are first connected to their energy sources, to heat them. After the cathodes 4 and 104 have reached the proper temperature for normal emission, the plate-supply battery 16 is connected into the output circuit. Assuming that the oscillator 2 starts oscillating first, the radio-frequency energy thus produced will travel around the impedance ele-

ment 39, due to transformer or inductive action. After leaving the output circuit of the tube 2, this energy will be impressed on the input circuit of the tube 102, which will amplify it, and then re-impress it upon the resonator circuit. The resonator circuit will then carry the energy around to the grid circuit of the tube 2 which, in turn, will build it up still further. This instantaneous build-up of the energy reaches a point where the Q of the circuit is the only limiting factor of the radio-frequency power produced.

If the wave form of Fig. 5 strictly depicts the true state of affairs accurately, the system will be free of harmonics, and the impedance 30 will resonate at the frequency for which it may be designed. The continuous impedance element 30 may therefore be termed a continuous electric resonator, and the output and input circuits of the oscillators constitute a portion of this resonator. The term "resonator" is more appropriate than "impedance," because the element 30 does not really offer any impedance to the flow of electric energy therethrough at the resonant frequency of the oscillatory system. The oscillatory circuit for each tube is a segment of the resonator. The wires connecting the plate-supply voltage to the tubes are usually not considered part of the oscillatory circuit, inasmuch as they are at ground or radio-frequency potential. The tubes are connected to these segments in such manner that, in progressing around the resonator, the output circuit of each oscillator is followed by the input circuit of the other oscillator. A rotating electric field is produced in the continuous resonator 30 by reason of the fact that the output of each oscillator is coupled to the input of the other oscillator. The electric tubes 2 and 102 are so connected to the impedance element 30, at the points of connection of opposite phase, that changes in polarity in the rotating field arriving at one of the two points of connection produce amplified changes in polarity at the second point substantially in phase with the field arriving at the second point. The intensity of the rotating field is thus increased, and its rate or period of rotation is sustained.

For use at high frequencies, the conductors 36 and 136 should be short. The diagram of Fig. 5 would not otherwise apply, and harmonics would be introduced through the presence of standing waves in these conductors. With long conductors 36 and 136, moreover, considerable losses might occur.

For very high frequencies, it may be desirable to employ one type of tube 2 or 102 rather than another; for example, the acorn tube. It has nevertheless been found that almost any conventional type of tube may be employed, even at the high frequencies, and beyond the cut-off-frequency rating specified by the manufacturer. Experience shows, for example, that it is possible to attain as much as thirty per-cent higher frequencies, for a given tube, than the manufacturer of the tube states to be possible when connected into a conventional circuit. This is an indication of the much greater efficiency that is obtained with the circuit of the present invention.

The superiority of the continuous-type resonator of the present invention over conventional resonators will be appreciated further when it is reflected that the magnetic field is concentrated within the resonator, thereby reducing eddy-current loss. It is therefore possible to shield

the resonator without introducing an appreciable loss in efficiency. The physical size of the resonator is much smaller than the size of conventional resonators designed to operate at the same frequency. Radiation losses are therefore reduced to a minimum.

The conductor 30 of Fig. 5 is shown in Fig. 6 bent into continuous circular form, with the end terminals 28, 128 connected together. Though Fig. 6 does not show so clearly as Fig. 5 that the terminals 28 and 128 are at zero radio-frequency potential, and the terminals 34 and 134 at maximum radio-frequency potential, with a phase difference of 180 degrees, it is diagrammatically more like the impedance element 30 already described. In actual practice, the impedance element 30 may be of wire, coiled, as before stated, into the form of a toroid, or doughnut shaped, as diagrammatically shown in Figs. 1, 2 and 4. This makes for compactness and lower cost, besides reducing the amount of radiation from it. As the doughnut structure is open, some radiation will nevertheless take place therefrom. The resonator, however, may be not only a toroid, as represented at 30, but also a coaxial ring 156, a cylinder, a sphere, and so on. In all cases, the rotating electric field before mentioned will be guided along a substantially circular electric path.

A greater degree of freedom from radiation loss may be obtained with the apparatus of Fig. 3, in which the impedance element 30 is shown replaced by a concentric-line resonator 156, which determines the frequency. The connections are very much the same as those above described, except that the conductors 36 and 136 are shown connected directly to the inner conductor 158 of the concentric line, instead of to the winding 30, as in Figs. 1, 2 and 4. The inner conductor 158 is shown containing the same parts 32, 38, 132 and 138, and the same six terminals 34, 28, 40, 134, 128 and 140 already described. The outer conductor 160 of the concentric line serves as a perfect shield, preventing radiation from the inductance of the inner conductor; further, it absorbs no radio-frequency energy.

The present invention makes it possible also to employ amplitude modulation on very high frequencies, without the disadvantages attendant upon the presence of frequency modulation, as occurs with conventional oscillators.

The frequency of the continuous-cascade operation of the present invention is remarkably constant, even at very high frequencies. Sustained operation may be obtained with the circuit of the present invention, even though the plate voltage should be reduced far beyond the point where conventional circuits cease to oscillate. Reference may be made, for example, to Fig. 7, containing a graph of the resonant frequency of the circuit plotted against the plate voltage of an 801 tube of the medium-power class. In a run with the tube at a 100-per-cent-rated plate voltage of 600, for example, 34.98 megacycles were obtained. The plate voltage was then reduced, by steps, to 1.5 volts, but the system continued to oscillate. No appreciable frequency change could be detected until the voltage was reduced from a normal 600 to 200. At the voltage of 200, conditions began to change. A change of 2300 per cent in plate voltage produced a change of approximately 0.1 per cent in resonant frequency. Another oscillator might have stopped oscillating at 100 volts, but this oscillator continued to

function with a plate voltage of only 1.5. This demonstrates the elimination of the external fields and the reduction of the radiation result in a high-Q circuit.

For a given rise in ambient temperature, moreover, the length of the conductor contained in the toroid increases; and since the toroid is physically continuous, this increase causes the distance between adjacent turns to increase, with a resulting decrease in the inductance of the coil. The increase in the length of the coil, on the other hand, causes an increase in the inductance. The net resultant change of inductance is small or negligible. Since the null points and the node points on the toroid are fixed in position, because of the manner of connecting the components of this system, no near-harmonic power can be generated. This feature contributes to the generation of more useable power than can be obtained from the use of conventional coils.

Owing to the mechanical rigidity and compactness of the oscillator of the present invention, as well as its high efficiency and its stability compared to the voltage characteristics, the oscillatory system of the present invention may be put to many uses. It is shown in Fig. 1 as feeding oscillatory energy to a dipole antenna 160, 162. The pole 160 of the dipole is connected by a conductor 164 to an adjustable terminal 166 of the resonator 30; and the pole 162, by a conductor 168, to an adjustable terminal 170. The terminal 166 is shown disposed between the fourth terminal 134 and the fifth terminal 128, and the terminal 170 between the first terminal 34 and the second terminal 28. The terminals 166 and 170 should be adjusted properly to yield the best results.

The operation of the three-phase radio-frequency-transmission carrier illustrated in Fig. 4 will be understood from the description already given. Three electron tubes 2, 102 and 202 are illustrated, instead of only two, forming parts of three oscillators, respectively connected as before described, but at three equi-angular spaced points of the resonator 30, instead of at two points. Corresponding points of connection for the adjacent-ly disposed vacuum tubes 2, 102 and 202 are spaced by angles of 120 degrees, and three terminals 172, 272 and 372 are consecutively at zero R. F. potential, with a time lag of 120 degrees.

The first part of the output and the input circuits of each oscillator is the same. It may be traced from the cathode 4, 104 or 204 of the respective tubes 2, 102 and 202, by way of the conductors 12, 112 or 212, through the energizing plate-supply B battery 16 and, by way of the conductor 18, to the terminal 172, which is connected to the terminals 272 and 372.

The connections of the tube 2 to the resonator 30 are substantially the same as described in connection with Figs. 1, 2 and 3, the grounded terminal 28 of Figs. 1, 2 and 3 being replaced by the grounded terminal 272.

From the grounded terminal 272, the output circuit of the tube 2 is completed, through the portion 32 of the resonator 30, to the fixed terminal 34 thereof and, by way of the conductor 36, to the anode 8. The remainder of the input circuit may be traced from the grounded terminal 272, through the portion 38 of the resonator 30, to the adjustable terminal 40 thereof; from the adjustable terminal 40, through the grid-coupling condenser 42, to the terminal 44; and from the terminal 44, by way of the conductor 46, to the control electrode 7.

From the grounded terminal 372, the output

circuit of the tube 102 is completed, through the portion 132 of the resonator 30, which is shown overlapping the portion 38, to the fixed terminal 134 thereof and, by way of the conductor 136, to the anode 108. The remainder of the input circuit of the tube 102 may be traced from the grounded terminal 372, through the portion 138 of the resonator 30, to the adjustable terminal 140 thereof; from the adjustable terminal 140, through the grid-coupling condenser 142, to the terminal 144, and from the terminal 144, by way of the conductor 146, to the control electrode 131.

From the grounded terminal 172, the output circuit of the tube 202 is completed, through a portion 232 of the resonator 30, which is shown overlapping the portion 138, to a fixed terminal 234 thereof and by way of a conductor 236, to the anode 208 of the tube 202. The remainder of the input circuit may be traced from the grounded terminal 172, through a portion 238 of the resonator, which is shown overlapping the portion 32, to an adjustable terminal 240 thereof; from the adjustable terminal 240, through a grid-coupling condenser 242, to a terminal 244; and from the terminal 244, by way of a conductor 246, to the control electrode 297 of the tube 202. A grid resistor 248, connected between the terminal 244 and the ground 222, serves as a bias for the input circuit of the tube 2. The portion 232 of the resonator 30 is connected in the output circuit of the third oscillator, between the cathode 204 and the anode 208, and the portion 238 of the resonator 30 is connected in its input circuit, between the cathode 204 and the control electrode 207.

A tri-pole antenna 260, 262, 264 may be connected to this three-phase system in a manner that will be understood from the description of the dipole antenna before described. The poles should be connected at points the right distance from the terminals 172, 272, 372, which are at ground potential, to produce proper matching for the feed-wire impedance.

It is not essential that the terminals 172, 272 and 372 be grounded by way of conductors corresponding to conductors 26 and 126; even if not so connected, they will still find their own grounds. The plate-supply voltage is shown connected to the terminal 172. It could be connected to the terminal 272 or 372 without affecting the operation.

The resonator is pulsed by each tube in turn, with a time-delay equivalent to 120 degrees. As each tube delivers a pulse to the resonator, a virtual ground appears at a point on the resonator approximately half way between the plate and the grid points of connection to the resonator. There are therefore three points of virtual grounds on the resonator, which appear and disappear as the tube connected to that segment, which includes this virtual ground point, delivers a pulse and then dies down. These three points of virtual ground therefore appear in rotation, with a time lag of 120 degrees.

The invention is not limited to the use of even the three-phase arrangement. Any desired number of oscillators may be embodied in the oscillatory system of the present invention, connected to the continuous resonator at symmetrically arranged points in such manner as to achieve the above-described continuous-cascade arrangement. The phase difference of the points of the continuous resonator at which n oscillators would be connected thereto would be $360/n$ degrees, and the output circuit of each oscillator

would be connected through the continuous resonator to the input circuit of the next adjacently disposed oscillator.

In all cases, since the vacuum tubes are connected across only a portion of the resonator, their internal capacitances are not the predominating tuning factors of the system.

The invention may be used also in meteorological work, radio-direction finding, very-high-frequency operations, radar, remote control of aircraft, the transmission and reception of telephony, as a submarine-detector, as a power source in microwave ground and aircraft communication, as a positive altimeter, in amplitude modulation, side-band transmission, and elsewhere. Because the system of the present invention does not respond to harmonics and, consequently, eliminates image response, it is particularly adapted for use in radio-receiving apparatus. The resonator may be utilized as an antenna tuning inductance, connected between the antenna and the receiving system.

A circuit that has vacuum tubes, working in an oscillatory condition, and the output circuits of which are connected or coupled to an antenna system, may be regarded as a transmitter. In order to utilize the system of the present invention for receiving purposes, the tubes may be prevented from oscillating, as by increasing the C bias or otherwise, with the possible exception of using the system with the feeble oscillations present for the reception of continuous-wave code transmissions by the "beat" system.

Other and further modifications will therefore occur to persons skilled in the art, and all such are considered to fall within the spirit and scope of the invention, as defined in the appended claims.

What is claimed is:

1. An oscillatory system having, in combination, a continuous resonator provided, in sequence, with first, second, third, fourth, fifth and sixth terminals, the first and the fourth terminals being of substantially opposite phase, the second and the fifth terminals being grounded, an oscillator having an input circuit connected between the second and third terminals and an output circuit connected between the first and the third terminals, and an oscillator having an input circuit connected between the fifth and sixth terminals and an output circuit connected between the fourth and sixth terminals.

2. An oscillatory system having, in combination, a resonator provided, in sequence, with first, second, third, fourth, fifth and sixth terminals, the first and the fourth terminals being of substantially opposite phase, the second and the fifth terminals being grounded, an oscillator having an input circuit connected between the second and third terminals and an output circuit connected between the first and the third terminals, and an oscillator having an input circuit connected between the fifth and sixth terminals and an output circuit connected between the fourth and sixth terminals, the system being provided with an output circuit having a terminal connected between the first and the second terminals and a terminal connected between the fourth and the fifth terminals.

3. An oscillatory system having, in combination, a continuous resonator provided, in sequence, with first, second, third, fourth, fifth and sixth terminals, an oscillator having an input circuit connected between the second and third terminals and an output circuit connected be-

tween the first and the third terminals, and an oscillator having an input circuit connected between the fifth and sixth terminals and an output circuit connected between the fourth and sixth terminals.

5. An electric system comprising a continuous single-element endless resonator having substantially uniformly distributed parameters and provided with a plurality of groups of first, second and third terminals in sequence, a plurality of oscillators, one corresponding to each group of terminals, each oscillator having an input circuit connected between the second and third terminals and an output circuit connected between the first and third terminals of the corresponding group of terminals.

10. In combination, a continuous mechanically and electrically re-entrant resonator having substantially uniformly distributed inductance and capacitance, means electrically bonding together symmetrically spaced points on said resonator operative to render said points substantially equipotential and defining at least two sectors of the resonator, an electric discharge device having input and output electrodes, means connecting the input electrode to one sector of the resonator intermediate the spaced points defining the same, and means connecting the output electrode to another sector of the resonator intermediate the spaced points defining said last-mentioned sector.

15. In combination, a continuous mechanically and electrically re-entrant resonator having substantially uniformly distributed inductance and capacitance and electrical length at least equal to one wavelength at the natural resonant frequency of the resonator, means electrically bonding together symmetrically spaced points on said resonator operative to render said points substantially equipotential and defining at least two sectors of the resonator, an electric discharge device having input and output electrodes, means connecting the input of electrode to one sector of the resonator intermediate the spaced points defining the same, and means connecting the output electrode to another sector of the resonator intermediate the spaced points defining said last-mentioned sector.

20. In combination, a continuous, single-element, annular resonator having substantially uniformly distributed inductance and capacitance, means electrically bonding together symmetrically spaced points on said resonator operative to render said points substantially equipotential, and means connected to said resonator intermediate said spaced points operative to sustain in said resonator electromagnetic standing waves for which the electrical length of said resonator is at least one wavelength.

25. In combination, an endless annular toroidal coil having substantially uniformly distributed inductance and capacitance and having its turns wound continuously in the same direction throughout, means electrically bonding together symmetrically spaced points on said coil operative to render said points substantially equipotential and defining at least two sectors of said coil, an electric discharge device having input and output electrodes, means connecting the input electrode to one sector of the coil intermediate the spaced points defining the same, and means connecting the output electrode to another sector of the coil intermediate the spaced points defining said last-mentioned sector.

30. In combination, an endless annular toroidal coil having substantially uniformly distributed

inductance and capacitance and having its turns wound continuously in the same direction throughout, means electrically bonding together symmetrically spaced points on said coil operative to render said points substantially equipotential, and means connected to said coil intermediate said spaced points operative to sustain in said coil electromagnetic standing waves for which the electrical length of said coil is at least one wavelength.
